CLAIM

An ornamental design for a portion of a soap dispenser, as shown and described.

DESCRIPTION

FIG. 1 is a front left perspective view showing our new design of a portion of a soap dispenser;

FIG. 2 is a right side view thereof, the left side view being a mirror image thereof;

FIG. 3 is a top view thereof;

FIG. 4 is a bottom view thereof;

FIG. 5 is a front view thereof; and,

FIG. 6 is a rear view thereof.

The broken lines in FIGS. 1-6 immediately adjacent to the shaded areas represent unclaimed boundaries of the design. The broken lines in FIGS. 1-6 that depict the remainder of the soap dispenser are for illustrative purposes only and form no part of the claimed design.
